UNITED STATES PATENT OFFICE.

N. S. LOCKWOOD AND J. D. WINN, OF DAYTON, OHIO.

IMPROVEMENT IN PLOWS.

Specification forming part of Letters Patent No. 15,137, dated June 17, 1856.

To all whom it may concern:

Be it known that we, N. S. LOCKWOOD and J. D. WINN, of Dayton, in the county of Montgomery and State of Ohio, have invented a new and useful Improvement in the Construction of Plows; and we do hereby declare that the following is a full, clear, and exact description of the same, reference being had to the annexed drawings, making a part of this specification, in which—

Figure 1 is a side view of the mold-board side of the metal portion of the plow. Fig. 2 is a side view of the opposite or land side of the same. Fig. 3 is a back view of the same. Fig. 4 is a side view of the land side of the same, showing a breast attached to the mold-board and share instead of a post, as shown in Figs. 1, 2, and 3.

The nature of our invention consists in a peculiar mode of attaching the post or breast to the mold-board, and in the peculiar mode of attaching the share to the mold-board, as will be presently shown and described.

To enable those skilled in the art to fully understand and construct our invention, we will proceed to describe it.

A, Figs. 1, 2, and 3, represents a cast-iron upright, commonly termed the "post," the upper part of which is firmly attached in the usual manner to the beam of the plow. B is the mold-board, constructed of cast-steel. The post A is welded to the front end of the mold-board, the dotted lines D in Figs. 1 and 2 showing the points of contact. The lower end of the post A has a horizontal flange, A', cast with it, said flange being welded to the inner side of the mold-board, as shown at E, Figs. 2, 3, and 4.

C represents the share, and C' is the landside, which are cast in one piece. The front ends of the share and landside are connected by a horizontal plate, C'', on which the lower end of the post A and flange A' rest. F F are screw-bolts, which pass through the flange A and plate C'' and firmly secure the mold-board and post to the share and landside.

By the above improvement in the construction of plows no bolt-heads are exposed on the outer side of the mold-board or share, and the mold-board may be hardened or properly tempered so that it will retain its original shape.

In case wooden posts are used, a breast, A'', may be welded to the mold-board B, as shown in Fig. 4, and the lower end of the wooden post attached to the breast by a screw-bolt, H. The only difference between the breast A'' and the post A is that the post is considerably higher than the breast, both being attached to the mold-board in the same manner.

Having thus described our invention, what we claim as new, and desire to secure by Letters Patent, is—

Welding the post A or breast A'' to the mold-board B and attaching the share C and landside C' to the mold-board and post or breast by means of the flange A' at the lower end of the post or breast and the plate C'' of the share and landside, through which flange and plate screw-bolts F F pass, substantially as shown, for the purpose specified.

N. S. LOCKWOOD.
J. D. WINN.
